UNITED STATES PATENT OFFICE.

CHARLES J. GREENSTREET, OF WEBSTER GROVES, MISSOURI.

PROCESS OF MANUFACTURING OLEFINS AND THEIR OXIDATION PRODUCTS.

1,110,925.

Specification of Letters Patent. Patented Sept. 15, 1914.

No Drawing.

Application filed June 7, 1912. Serial No. 702,176.

To all whom it may concern:

Be it known that I, CHARLES J. GREENSTREET, a citizen of the United States, and a resident of the city of Webster Groves, in the county of St. Louis and State of Missouri, have invented a new and useful Process of Manufacturing Olefins and Their Oxidation Products, of which the following is a specification.

10 The principal objects of my invention are to devise a practical method of manufacturing olefins from mineral oils and also to devise a practical method of manufacturing alcohols, aldehydes and fatty acids therefrom.

15 The invention consists in the hereinafter described treatment of mineral oil to obtain a large proportion of olefins therefrom.

It also consists in the oxidation of olefin 20 to obtain alcohols, aldehydes and acids therefrom. It also consists in the steps and processes hereinafter more fully described.

25 The liquid product resulting from the treatment of crude oil by the so-called "cracking" process is a mixture consisting almost wholly of paraffins with a comparatively small quantity of olefins. The liquid product resulting from the treatment of crude oil by a process invented by me and

30 described in my co-pending application Ser. No. 696,891, filed May 13, 1912, is a mixture consisting of paraffins with a considerable proportion of olefins. As more fully described in said application, my said process

35 consists in forcing the crude oil to and through an atomizer on the inlet side of a coil of pipe of uniform diameter kept at a substantially cherry red temperature, the oil being thoroughly commingled at the atomizer with steam under a considerable pressure, say about one-hundred pounds per

40 square inch, the quantity of steam being that of a column of water substantially equal to or greater than the volume of the oil. In

45 order to increase the production of olefin, the product resulting from the treatment just described is itself submitted to the same treatment; that is, the condensate resulting from the passing of the crude oil through

50 a long hot coil under the conditions above stated, is again passed through such a coil under substantially the same conditions. In consequence of this repeated operation, the resulting product contains a very large percentage of olefins.

Whether the mixture of paraffins and ole-

fins is obtained by the "cracking" process or by my said process, or otherwise, sulfuric acid is added thereto in sufficient quantity to convert the olefins into the corresponding sulfonic ethers. Water is then added to convert such ethers into the corresponding alcohols. In the meanwhile, the paraffins remain unchanged. For some purposes, it may be unnecessary to separate the paraffins from the alcohols. Usually, however, it will be desirable to separate the paraffins from the alcohols; and in order to accomplish such separation, the mixture is subjected to the process of fractional distillation. Fractional distillation is especially available for such separation by reason of the fact that, whereas olefins and paraffins of substantially the same specific gravity distil at nearly the same temperatures, there is a very wide difference in the distillation points of paraffins and the corresponding olefins on the one side compared with the alcohols derived therefrom on the other. Thus, while the olefin C_8H_{16} distils at a temperature of one hundred and twenty-three degrees centigrade, the corresponding alcohol $C_8H_{18}O$ distils at a temperature of from one hundred and eighty to one hundred and ninety degrees centigrade.

When it is desired to convert the olefins of the mixture into the aldehydes or acids, a strong oxidizing agent, such as chromic acid or alkaline permanganate of potassium may be used. The result of the reaction of these last mentioned reagents upon the olefins is to convert them into alcohols, aldehydes and acids. Hypochlorous acid unites also with the olefins to form chlorhydrins which can be converted into corresponding oxids, as for instance, by heating with a solution of caustic soda or other caustic alkali.

It is noted that whether the olefins are treated with sulfuric acid or with hypochlorous acid or with chromic acid or alkaline permanganate of potassium, the general result in each case is an oxidation of the olefin. It is further noted that (with the exception of hypochlorous acid) all of these reagents effect a direct oxidation of the olefins, that is, oxidation with a single reagent, whereas treatment with hypochlorous acid indirectly brings about oxidation, that is, treatment with hypochlorous acid produces an intermediate compound which requires an additional reagent to effect oxi-

dation thereof by substitution. These reagents react to produce different specific results; and the choice of a reagent will depend to a certain extent upon the product desired. Instead of the reagents specified, their proper chemical equivalents may be substituted therefor. For instance, hydrochloric acid may be used as a substitute for sulfuric acid and constitutes an equivalent therefor, but in such case, hydrochloric ether is formed instead of sulfonic ether, and such hydrochloric ether is immediately converted into alcohols in the same manner as the sulfonic ether. Likewise, it is obvious that the presence of the paraffins is not of any importance in the treatment of the olefins.

What I claim as my invention and desire to secure by Letters Patent is:

1. The process of manufacturing olefins which consists in forcing mineral oil commingled with steam through a long coil of continuous pipe at a substantially cherry red

heat, and repeating the operation upon the resulting product.

2. The process of treating crude oil which consists in forcing it commingled with steam through a long continuous coil of pipe at a substantially cherry red heat, and oxidizing the olefin ingredients of the resulting product.

3. The process of treating crude oil which consists in forcing it commingled with steam through a long continuous coil of pipe at a substantially cherry red heat, oxidizing the olefin ingredients of the resulting product, and separating the oxidation product by fractional distillation.

Signed at St. Louis, Missouri, this 5th day of June, 1912.

CHARLES J. GREENSTREET.
